UNITED STATES PATENT OFFICE

2,308,107

MARKING MACHINE

Charles F. Robbins and David F. Putnam, Keene, N. H., assignors to Markem Machine Company, Keene, N. H., a corporation of New Hampshire

Original application February 5, 1941, Serial No. 377,446. Divided and this application July 21, 1941, Serial No. 403,308

1 Claim. (Cl. 101—217)

This invention relates to marking machines of that type in which the printed impression is applied to the work by a manually manipulated transfer roll which is separable from the other parts of the machine and which can be temporarily assembled with such other parts for the purpose of receiving an ink impression that is subsequently transferred to the work by the manual manipulation of the transfer roll.

In our co-pending application, Serial No. 377,446, filed February 5, 1941, of which this is a division, there is illustrated a marking machine of the above type which comprises two rotary type-carrying members, each having a type element mounted thereon, means to give said type-carrying members a cyclic movement by which each type element is moved through a path that begins and ends at the same point, a transfer roll rotatably mounted in a holder therefor which is separable from the machine frame and is capable of being manually placed in the frame in an operative position in which it is so located as to receive an ink impression from the type elements as the type-carrying members are rotated, and means to rotate the transfer roll when it is in its operative position, thereby to provide a rolling contact between the said roll and the type elements by which the latter lay an ink impression on the transfer roll, said holder being capable of being manually removed from the frame and manually manipulated to transfer the ink impression thereon to the article to be marked.

In the machine illustrated in said application, the means for operating the type-carrying members is such that at the end of each operation of the machine, said members are brought to rest in a predetermined angular position, and the transfer roll is so constructed that it can only be introduced into the machine or removed therefrom when both it and the type-carrying members are in predetermined relative angular positions.

With this arrangement, the ink impression which each type element lays on the transfer roll will always be located on said roll in a predetermined position, and upon repeated operations of the machine, the successive ink impressions which each type element applies to the roll will register exactly with each other.

With this construction, it is not necessary to clean the transfer roll between successive operations.

In a machine having two type-carrying members, it is usually the practice to use a type element on each type-carrying member which is designed to print a part only of the complete print- 55

ed impression, the type element on one type-carrying member being adapted to apply to the transfer roll an imprint corresponding to part of the complete printed impression, and the type element on the other type-carrying member being constructed to apply an ink impression to the transfer roll corresponding to the remaining portion of the complete printed impression.

These machines are also usually made with interchangeable type elements which can be removed from the type-carrying members and replaced by other type elements adapted to make a different printed impression.

In the machine shown in our co-pending application, Serial No. 377,446, means are provided for holding the transfer roll in a fixed position during the time that it is receiving its ink impression from the two type members, and in order to make a perfect ink impression on the transfer roll, it is important that the two type-carrying members should be properly adjusted relative to each other and to the transfer roll when the latter is in its fixed operative position, so that neither ink impression will be either too light or too heavy relative to the other ink impression.

It is, therefore, one of the objects of our invention to provide novel means for supporting the type-carrying members and so adjusting them relative to each other and to the transfer roll when the latter is in its fixed position that each type member will make a proper ink impression on the transfer roll.

In the drawings wherein we have illustrated 35 an embodiment of our invention:

Fig. 1 is a front view of an offset marking machine embodying the invention with the transfer roll removed.

Fig. 2 is a view looking to the right, Fig. 1, with the casing removed and the transfer roll shown in dotted lines.

Fig. 3 is a section on the line 3—3, Fig. 1, showing the means for rotating the type-carrying members and the transfer roll.

Fig. 4 is a fragmentary sectional view showing the means for supporting and adjusting the shafts for the type-carrying members.

Fig. 5 is a section on the line 5—5, Fig. 4.

Fig. 6 is a section on the line 6—6, Fig. 5.

Fig. 7 is a fragmentary perspective view of the transfer roll.

Figs. 8 and 9 show two type elements, each of which is adapted to make an ink impression corresponding to part of the complete ink impression that is to be transferred to the work.

Fig. 10 is illustrative of the complete ink impression.

The machine herein illustrated comprises two rotatable type-carrying members 3 and 4 which are mounted on rotary shafts 6 and 7. These shafts are journaled in the frame 8, and each shaft has a sprocket wheel 11 thereon which meshes with and is driven by an endless sprocket chain 12, the sprocket wheel on the lower shaft 7 not being visible in Fig. 1. This sprocket chain 12 is driven from a shaft 48 through the medium of a one-revolution clutch indicated generally at 54, one of the clutch elements being provided with a sprocket wheel 47 which meshes with and drives the sprocket chain 12. The shaft 48 is connected by suitable gearing 53, 52 to a shaft 51 of a motor 49.

The driving connections above referred to between the motor 49 and the sprocket chain 12 are the same as those described in detail in our co-pending application, Serial No. 377,446, to which reference may be had.

Each rotary type-carrying member 3 and 4 carries on its periphery a type element, said type elements being indicated at 5 and 5a. Each type element is made so as to print a part only of the complete printed impression to be made.

For purpose of illustrating, we have assumed that the complete printed impression comprises the word "markem," as indicated at 5b in Fig. 10 with a rectangular border 5c enclosing the word. The type element 5 may carry type characters to print the word "markem," as shown in Fig. 8, and the type element 5a may carry a type character adapted to print a rectangular border 5c. Ink is supplied to the type members 5, 5a by means of inking rolls 34 which operate in ink reservoirs 33, each inking roll having a shaft 35 which is journaled in the corresponding reservoir. These reservoirs are suspended from studs 37 extending from the frame 8 and are held in adjusted position on the studs by clamping screws 39.

The shaft 35 of each inking roll is driven from a sprocket wheel 41 that meshes with the sprocket chain 12. This inking appliance is the same as that illustrated in our co-pending application, Serial No. 377,446.

The clutch device 54 is tripped by a trip lever 66 which is mounted on a rock shaft 63, the construction being such that when the trip lever 66 is depressed from its position shown in Fig. 2, the clutch 54 will be engaged and the rotary type-carrying members 3 and 4 will each be given one complete rotation, said clutch element operating to bring said members to rest when each has completed its single rotation.

The transfer or offset roll which receives an ink impression from each of the type elements 5, 5a, and by which this ink impression is transferred to the work, is indicated at 13. This transfer roll is carried in a holder 15 which is provided with two arms 16 in which the transfer roll is rotatably mounted, and which is also provided with a handle 17 by which it may be manually manipulated. The transfer roll, which may be of rubber or synthetic rubber-like material that will take a good ink impression, is mounted on a shaft 14, the ends of which project through the arms 16 of the holder 15 and form trunnion portions 18. The frame of the machine is formed with two pairs of supporting arms 25, 26, the arms of each pair forming between them an open-ended slot 27 into which the trunnion portions 18 of the shaft 14 may be inserted, these

two pairs of arms 25, 26 being spaced apart a proper distance to receive between them the forked portion 16 of the holder 15. The transfer roll is introduced into the machine to receive its ink impression by entering the trunnions 18 into the open ends of the slots 27, and when the roll is in a position in which the trunnion portions 18 bottom against the inner end of the slots 27, then said roll will be in an operative position to receive an ink impression from each of the type elements 5 and 5a when the type-carrying members are rotated.

The machine is provided with means for positively rotating the transfer roll in synchronism with the type-carrying members 3 and 4 when the latter are rotated, and for this purpose, the trunnion portion 18 of the shaft 14 of the transfer roll 13 is provided with a wedge-shaped slot 32 which is adapted to receive the wedge-shaped end 31 of a shaft 29 which is journaled in the frame 8 and is provided with a sprocket wheel 30 which meshes with and is driven by the sprocket chain 12.

When the machine has been brought to rest by the clutch 54 at the end of any operation, the shaft 29 will always be positioned with the narrow edge of the wedge 31 directed toward the open end of the slot 27.

When the transfer roll 13 is angularly positioned in its holder 15 with the wide end of the slot 32 directed away from the handle 17, as shown in Fig. 7, then said transfer roll can be inserted into its operative position in the machine, and as the transfer roll approaches its operative position, the wedge-shaped end 31 of the shaft 29 will enter the wedge-shaped slot 32 of the shaft 14, thereby coupling the shafts 29 and 14 together, so that when the machine is started in operation, the transfer roll 13, as well as the type-carrying members 3 and 4, will be positively rotated. The sprocket wheel and sprocket chain construction for rotating the shafts 6, 7 and 29, is such that the transfer roll 13 will be rotated at the same surface speed as the type-carrying members 3 and 4. In the construction herein shown, the transfer roll is only one half the diameter of the type-carrying members 3 and 4, and the sprocket wheel and sprocket chain construction operate to rotate the transfer roll 13 twice for each single rotation of the type-carrying members 3 and 4. In operating the device, the transfer roll is inserted into the machine as shown by dotted lines in Fig. 2, thereby coupling its shaft 14 with the shaft 29, and then the clutch 54 is tripped by the trip lever 66 and the type-carrying members 3 and 4 are each given one complete rotation while the transfer roll is given two rotations, during which each type element 5 and 5a lays an ink impression on the transfer roll, the ink impression left by the type element 5 comprising the word "markem," and the ink impression left by the type element 5a being in the form of a rectangular border 5c which encloses the word "markem." These two ink impressions are laid on the transfer roll 13 in exact registry with each other, thereby to form the complete impression to be transferred to the work.

The clutch 54 will bring the parts to rest in the position shown in Fig. 1 with the wedge-shaped portion 31 of the shaft 29 extending horizontally, so that the transfer roll, with its ink impression therein, can be readily withdrawn from the machine, after which it can be rolled over the work to transfer the ink impression there-

to. In the device herein illustrated, the holder 15 is provided with an arm 67 having an offset portion 68 by which the trip lever 66 can be tripped so that when the transfer roll has been inserted into the machine, the clutch can be thrown into operation by merely swinging the handle 17 of the transfer roll downwardly to cause the end 68 of the arm 67 to engage and depress the trip lever 66.

Since the complete ink impression which is formed on the transfer roll 13 is constituted by the two ink impressions which the two type members 5 and 5a apply to said transfer roll, it is, of course, important that each type member 5 or 5a should have the same printing pressure on the transfer roll during the operation of the machine.

The fact that the type members 5 and 5a are removable and interchangeable makes it necessary to provide some form of adjustment to enable both type elements to have the same printing pressure on the transfer roll.

When the transfer roll is in the machine, it is maintained in a fixed position by reason of the trunnions 18 being supported in and bottoming against the ends of the slots 27.

In the present embodiment of the invention, the adjustment between the type-carrying members and the transfer roll when the latter is in its operative position is secured by mounting each shaft 6 and 7 in an adjustable bearing support so as to permit each shaft to be adjusted toward and from the transfer roll when the latter is in its operative position as necessary to obtain the same printing pressure between each of the type elements and the transfer roll.

In the present embodiment of the invention, each shaft 6 and 7 is mounted in suitable ball bearings 10 which are carried by a housing 130, each housing being adjustably mounted in the portion 8 of the frame so as to provide for vertical adjustment of each of the shafts 6 and 7.

Each housing 130 is formed with a circular portion 131 which fits within a circular opening 132 with which the frame 8 is provided. This circular portion 131 of the housing 130 is eccentric with relation to the axis of the shaft 6 or 7 so that the turning of the housing within the aperture 132 on its eccentric portion 131 will produce an orbital movement of the shaft 6 or 7 and thus cause each shaft to be raised or lowered relative to the frame 8.

Each housing 130 is clamped in any adjusted position by means of two clamping blocks 135, each clamping block having a lip 140 which overlies a peripheral flange 134 with which the housing is provided. This flange 134 is concentric with the circular wall of the eccentric portion 131 of the housing, or, in other words, is concentric with the opening 132 in the frame 8. 60

Each clamping block 135 is clamped to the frame 8 by a clamping screw 136, and when the clamping screws are tightened, the lips 140 of the clamping blocks have sufficient clamping engagement with the annular flange 134 to lock the housing in its adjusted position.

By this means, either type-carrying member 3 or 5 may be adjusted vertically as necessary to produce the proper printing pressure between its type member and the transfer roll.

Although the vertical adjustment of each shaft 6 or 7 involves a movement of the said shaft in a horizontal direction because of the orbital motion of the shaft during the adjusting operation, yet since the shafts 6 and 7 are driven from the sprocket chain 12, any adjustment of the shafts does not in any way interfere with the driving connection between the driving sprocket wheel 47 and the sprocket wheels 11 for the shafts 6 and 7.

The sprocket chain 12 is held under proper tension by a tensioning sprocket wheel 116 around which said sprocket chain 12 passes, and which is mounted on a stud 117 carried by a bracket 118 that is pivoted to the frame at 119. This bracket is acted on by a pulling spring 120, one end of which is anchored to the frame 8 at 121, and the other end of which is connected to the hooked arm 122 of the bracket 118. The tension of the spring 120 tends to swing the sprocket wheel 116 downwardly and thereby the sprocket chain is held under the uniform and proper tension, notwithstanding any adjustment which may be made in the shafts 6 and 7 and their sprocket wheels 11.

We claim:

A marking machine of the class described comprising a frame having a vertical wall provided with two circular openings therethrough, a bearing member in each opening, each bearing member having a circumferential flange which overlies one face of said wall and being turnable about its axis in its opening, clamping blocks secured to the wall and engaging the flange of each bearing member and operating to clamp it in any adjusted angular position, a shaft journaled in each bearing member eccentrically thereof, each shaft extending beyond its bearing member at both ends and thus having two free ends, a type-carrying member fixed on one free end of each shaft, a sprocket wheel fixed on the other free end of each shaft, a sprocket chain engaging said sprocket wheels and operating to rotate the type-carrying members, a transfer roll, and means normally mounting the transfer roll in an operative position in which it is adapted to receive an ink impression from each type-carrying member.

CHARLES F. ROBBINS.
DAVID F. PUTNAM.
